UNITED STATES PATENT OFFICE.

JOHN A. CAMPBELL, OF CARBONDALE, ILLINOIS.

HATRACK FOR AUTOMOBILES.

Application filed September 13, 1923. Serial No. 662,567.

To all whom it may concern:

Be it known that I, JOHN A. CAMPBELL, a citizen of the United States, and a resident of Carbondale, in the county of Jackson and State of Illinois, have invented a new and Improved Hatrack for Automobiles, of which the following is a full, clear, and exact description.

This invention relates to a hat rack for automobiles, and has for an object the provision of a simple, durable, efficient hat rack which can be readily applied to any type of automobile without requiring any modification or alteration in the construction of the car and can be disposed therewithin in easy access to the people in the car and yet out of the way so as not to be an inconvenience.

Another object concerns the provision of means whereby the rack can be made easily adjustable to receive different sizes of hat gear.

A further object concerns the provision of a hat rack which can be constructed and adapted to harmonize with any type or design of car.

The invention is illustrated in the drawings, of which—

Figure 1 is a section through a car looking forward to the hat rack in the top;

Fig. 2 is a plan view, partly in section, of the hat rack; and

Fig. 3 is a detail section of one end of one of the hat rack members.

The form of the invention shown in the drawings is a preferred form, although it is understood that modifications in the construction and arrangement of the parts and in the character of the materials used may be adopted without departing from the spirit of the invention.

Broadly, my invention includes a pair of resilient members extending across the car beneath the top and substantially parallel to each other so that head gear can be received and disposed beneath said members along their length. The ends of these members are adjustably connected to suitable fastening means at each end whereby the distance between the members throughout their length can be made variable to suit

the type or size of head gear which it is desired to hold therebetween.

More specifically, the invention includes a pair of coiled springs disposed substantially parallel across the car beneath the top, the ends of each spring being connected to a metallic bar in such a manner as to be adjustable along the bar so that the distance between each spring and its fellow spring can be varied.

As shown in the drawings, the invention comprises a pair of coiled springs, such as 1 and 2, extending across the car beneath the top, each of these springs being in any suitable manner covered by fabric such as 3 which is preferably rubber cloth. The design and coloring of this cloth can be made to harmonize with the furnishings of the car. Each end of each spring is formed in a loop 4 which is adapted to engage with a similar loop 5 on the end of a hook 6. This hook can be easily engaged along the length of a metallic bar or frame 7, which, in the form shown, is a wire made with a plurality of kinks and of a substantially wavelike form to permit the hook 6 at the end of each wire to be disposed in any one of the kinks. The ends of each bar 7 are fastened to the bows 8 at the top of the car, or to some other convenient foundation as circumstances warrant. It will be noted that the end of each coil is surrounded by a sleeve 9 having one end threaded as at 10 and closed by a screw-threaded cap 11 having an aperture 12 through which the stem of the hook 6 extends. This is for the purpose of hiding the connection between the hook 6 and the end of the coil spring, thus making the construction one having a simple and neat appearance.

By disposing the hooks 6 in more closely adjacent kinks or curved portions of the bars 7, the distance between the coils can be varied so that larger or smaller hats or head gear can be held in position.

What I claim is:—

1. A hat rack for automobiles having a top portion, which includes a pair of coiled springs extending across the car beneath the top, a flexible fabric covering said springs, a hook at each end of each spring

loosely connected thereto, a metal bar connected to each side of the top portion of the automobile, and means on said bar whereby the hooks on the end of the spring can be adjustably connected thereto.

2. A hat rack for automobiles, which includes a pair of coiled springs extending across the car beneath a top thereof, a pair

of metallic wires formed in a kinked or corrugated form and attached to the top of the car at each side, and hooks on the ends of the coiled springs to be adjustably engaged with any desired portion of said wires along their length whereby the distance between the springs can be varied.

JOHN A. CAMPBELL.
